[57] CLAIM

The ornamental design for a combined computer game
and television set, as shown and described.

DESCRIPTION

FIG. 1 is a top, front and right side perspective view of
a combined computer game and television set according
to the present invention;

FIG. 2 is a view similar to FIG. 1 illustrating the tele-
vision set with the control panel in an open condition and
a remote controller attached to the television set;
FIG. 3 is a top plan view of the television set illustrated
in FIG. 1;

FIG. 4 is a front elevational view thereof;
FIGS. 5 and 6 are right and left side elevational views,
respectively, thereof;
FIG. 7 is a rear elevational view thereof; and,
FIG. 8 is a bottom plan view thereof.
